UNITED STATES PATENT OFFICE.

GEORGE E. BULL, OF MONESSEN, PENNSYLVANIA, ASSIGNOR TO PITTSBURGH STEEL COMPANY, OF PITTSBURGH, PENNSYLVANIA, A CORPORATION OF PENNSYLVANIA.

REEL.

Application filed November 21, 1922. Serial No. 602,421.

To all whom it may concern:

Be it known that I, GEORGE E. BULL, a citizen of the United States and resident of Monessen, in the county of Westmoreland 5 and State of Pennsylvania, have invented a new and useful Improvement in Reels; and I do hereby declare the following to be a full, clear, and exact description thereof.

My invention relates to reels.

10 The object of my invention is to provide a reel adapted for holding bundles of wire-fabric, such as a wire-fabric comprising stay-wires and strand-wires welded or otherwise connected at their point of intersection. In the manufacture of such fabric the said fabric, as it comes from the machine, is wound around a spool at the rear of the machine, and said spool usually consists of two semi-circular members so that the end 15 of the fabric may be inserted between the members and then the members clamped together to form the spool around which the fabric as it is made is wound. When the roll has reached its full diameter the spool 20 is removed from the machine and the semi-circular members composing the same are driven out from one end of the roll, leaving the portion of the fabric which was clamped between the members of the spool extending 25 across the bore or central opening through the roll in the form of a web.

When the fabric made up into such rolls is to be used in the making of other forms of fabric, such as where it is to be used in 30 connection with a machine for attaching a paper backing to the wire fabric to be employed in construction work in connection with the walls and ceilings of buildings, it is necessary to mount this roll of fabric on a 35 reel, and the reel of the present application is particularly adapted for such purpose.

In the accompanying drawing, Fig. 1 is 40 a longitudinal section of my improved reel; Fig. 2 is an end view; Fig. 3 is an end view 45 of a portion of the roll of fabric looking in at one end; and Fig. 4 is an enlarged detail of one of the spindles.

50 In the drawing the numeral 2 designates a suitable base-plate upon which the reel is mounted, and secured to said base-plate are the standards 3 and 4, said standards being connected to said base-plate by the screws 5 in the threaded openings 6 in said base-plate, and a number of said openings may

be arranged at intervals on said base-plate 55 to provide for the adjustment of the standard 3 at different distances from the standard 4, according to the length of the bundle to be mounted on the reel.

A short spindle 7 is mounted in the standard 3, said spindle being held in position against rotation by the set-screw 8. The spindle 7 has the annular groove 9 formed in the projecting bearing portion 10 on which is mounted the revoluble conical-head 60 11, the sleeve-portion 12 of the said head, which fits around the bearing 10, having the opening 13 through which the screw 14 passes, and which enters the annular groove 9. In this manner provision is made for the 65 free rotation of the conical-head 11 on the bearing 10 of the spindle 7 which is held stationary in the standard 3.

A spindle 15 is mounted in the standard 4, said spindle having the bearing portion 70 16 with the annular groove 17. A conical-head 18 engages the bearing 17, and a screw 19 holds the conical head 18 on said bearing and permits free rotary movement of 75 said head in the same manner as the conical-head 11.

To provide for the longitudinal movement of the spindle 15, I provide the lever 20 pivoted at 21, the said lever having the slot 22 which is engaged by the pin 23 passing through the bifurcated end 24 of the spindle 15.

Secured to the standard 4 is the bracket 25 which is provided with the ratchet-teeth 26 in position to be engaged by the pawl 27 80 on the lever 20.

When it is desired to mount a roll of fabric on the reel, the fabric-roll 28 is mounted on the skid 29 and is brought up into position to be engaged by the conical-heads 11 85 and 18, said heads being in alignment with the bore 30 at the center of the roll. As above stated, the rolls as they come from the spools on which they were originally wound have the web 31 which divides the bore of 90 the roll, and the conical heads 11 and 18 are provided with the slots 32, which slots are brought into register with the web 31, whereupon by moving the upper end of the lever 20 inwardly the conical head 18 is 100 forced into one end of the roll of fabric, and this will act to force the roll on to the opposite conical head 11, and by pushing 105

on said lever a secure hold is obtained on the roll so that it will rotate with said conical-heads. When this has been accomplished the pawl 27 engages the ratchet-teeth 26 and holds the heads securely in this position.

The fabric may then be fed from the roll at any desired speed, the conical-heads 11 and 18 rotating freely on the spindles and the roll of fabric is accurately centered so that an even feed will be obtained, which is very important in feeding the fabric to a machine such as that referred to above.

What I claim is:

1. A reel for a fabric roll having an axial bore and a web extending diametrically across said bore, comprising a frame, and heads carried by said frame in position to extend into the ends of said bore, the said heads being provided with diametral recesses within which the edges of said web may seat.
2. In a reel, the combination with a standard, a spindle held therein, said spindle having a bearing portion with an annular groove, a head engaging said bearing portion, a screw passing through said head engaging said annular groove, a second stand-

ard, a longitudinally movable spindle mounted therein having a bearing portion with an annular groove formed therein, a head engaging said bearing portion, a screw passing through said head engaging said annular groove, a lever connected to said last-named spindle, and means for locking said lever in different positions.

3. In a reel, the combination with a standard, a spindle held therein, said spindle having a bearing portion with an annular groove, a head engaging said bearing portion, a screw passing through said head engaging said annular groove, a second standard, a longitudinally movable spindle mounted therein having a bearing portion with an annular groove formed therein, a head engaging said bearing portion, a screw passing through said head engaging said annular groove, a lever connected to said last-named spindle, a ratchet on said second standard, and a pawl on said lever engaging said ratchet.

In testimony whereof I, the said GEORGE E. BULL, have hereunto set my hand.

GEORGE E. BULL.
